DESIGN.

C. W. LINK.

AUTOMOBILE TOP.

APPLICATION FILED DEC. 10, 1917.

51,889.

Patented Mar. 19, 1918.

Inventor:

Charles W. Link,

by *Edward J. Straus,*

Atty.

UNITED STATES PATENT OFFICE.

CHARLES W. LINK, OF LOS ANGELES, CALIFORNIA.

DESIGN FOR AN AUTOMOBILE-TOP.

51,889.

Specification for Design.

Patented Mar. 19, 1918.

Application filed December 10, 1917. Serial No. 206,557. Term of patent 3½ years.

To all whom it may concern:

Be it known that I, CHARLES W. LINK, a citizen of the United States, residing at Los Angeles, in the county of Los Angeles and State of California, have invented a new, original, and ornamental Design for Automobile-Tops, of which the following is a specification, reference being had to the accompanying drawing, forming part thereof.

The figure is a side elevation of an automobile top, showing my new design.

I claim:

The ornamental design for an automobile top, as shown.

CHARLES W. LINK.

Witnesses:

JEANETTE CHILDS,
WALTER DICK.
